CONTAINER BOTTOM AND TOP SPINNING HEAD

John K. M. Harrison, Orono, Pa.

Application March 22, 1939, Serial No. 263,349

5 Claims. (CL 93—36.5)

This invention has reference broadly to means operative to spin over the ends of containers, after suitable end closures have been inserted therein, into overlapping relation with the confronting inner surface of the container body shell, as well as to rigidly buttress-seal the surrounding free ends in contact with the respective end closures against outward displacement.

More particularly, the present improvements aim to provide a novel construction of container end spinning head whereby the retroverted portion of container body shell ends is not only more evenly distributed and uniformly forced into mutual union with the confronting inner surface of said body shell, but the operation as a whole is effectively accomplished in less time than hitherto.

Another aim of this invention is to attain the stated object of the preceding paragraph under the action of irradiant heat with a minimum of frictional resistivity to its easy accomplishment and, at the same time, to expansively roll the body shell retroversion radially outwards into mutual union with the confronting body shell surface, as well as longitudinally-inwards to sealing juncture with the container end closure surrounding edge portion.

Further objects and ancillary advantages of this invention will appear from the following disclosure of preferred embodiments when considered in conjunction with the accompanying sheet of drawings; while it is to be understood the concluding claims are to be accorded a range of equivalents consistent with the state of the prior art.

In the drawing:

Fig. I is a view partly in elevation and partly in axial section of one practical embodiment of this invention, with one end portion of a container therein.

Fig. II is an underside plan view of the same, with the container in section on the plane II—II of Fig. I.

Fig. III is a fragmentary section of a structural detail, hereinafter fully explained, but drawn to a larger scale.

Fig. IV is a similar view to the preceding, showing a roller construction hereinafter more fully explained.

Fig. V is a fragmentary view of a modified form of the invention; and,

Fig. VI is a similar view of a further modification.

In all the views, corresponding reference characters are applied to similar parts, but with

figure distinguishing exponents and additional indicia to better designate the differentiating features.

In the respective illustrations, there are shown typical rotary heads for spinning and sealing a closure 6, Fig. I, into the open end of a container body shell 7. More specifically, the illustrated embodiments of this invention are designed, preferably, for the sealing-in of pre-inserted end closures into suitably lined body shells under the action of irradiant heat with concurrent inward retroversion of the body shell ends into mutual juncture, as well as the bonding-buttress union of the turned portion against the outer peripheral edge of said closures.

In Figs. I and II, the spinning head is comprehensively designated 8, the same including a body portion 9, with a tubular attaching section 10, for example, and said body portion is formed to provide an interior coaxial boss 11 with a surrounding annular recess 12 having a flaring entrant portion 13. The boss 11 is preferably provided at diametrically opposed points with substantially circular cut-outs 14, axially of each of which is rigidly secured a flat-head, shouldered screw-stud 15, affording free rotary support for a ball-bearing roller 16 of a thickness slightly less than the depth of the housing 14 so as not to project beyond the face of the boss 11. It is to be observed, more particularly from Fig. II, that the respective studs 15 rigidly secure the inner race 31 of the rollers 16 in position and that they are located equi-distant from the axis of the head 8, so that the outer race 32 of the rollers 16, supported thereby, project evenly beyond the circumferential surface of the boss 11 or into the recess 12. Also the roller races 32 are freely sustained by balls 33 held in place by conventional retainers 34 and, preferably, have their circumferential edges slightly rounded at 17; while the inner end of the annular recess 12 is rounded slightly outwards at 18 to constitute a return bend functional to direct the retroversion 19 of the body shell 7 into impinging engagement with said body shell.

Mounted in an appropriate manner on the head 8 is an electric disc heater 20 whereby irradiant heating of the body portion 9 is effected in an obvious manner; while the outer face of the boss 11 is slightly dished at 21 to provide a circumferential ridge for contacting the outer surface of the closure 6.

In use, and assuming the spinning head 8 to be rotated by any suitable means, such for example as disclosed in my prior application for a patent

on machines for making, filling and sealing containers lined with a thermoplastic, filed October 11, 1937, under Serial No. 168,345, and which has matured into United States Patent No. 2,180,954, dated November 21, 1939, and that a preformed body shell 7 with a fully inserted end closure 6 is brought into registration with said head, either by elevation of such shell till its free edge enters the flaring 13 and annular recess 12; or by lowering of the rotary head 8 thereover, in an obvious manner. Incidental to entrance of the body shell 7 into the annular recess 12, it will be understood that its interior thermoplastic lining, as well as the entered portion of the body shell 7, will become heated and rendered pliable by irradient heat from the disc 20. It will, likewise, be clear that when the body shell 7 free edge contacts the recess return bend edge 18, it will be inwardly turned with the retroversion 19 surroundingly spun into mutual union with the confronting body-shell coated wall. Furthermore, as the intially retroverted portion 19, or its leading edge, impinges the upper rounded edge portion 17 of the rollers 16, as viewed in the drawing, it will be outwardly expanded and forcibly compressed, until said leading end passes below the lower edges 17 of said rollers and into circumferential abutment with the confronting circumferential portion of the end closure 6, whereby a uniform and bonding-juncture between the stated parts is positively effected.

Referring to Fig. V, all parts previously described are correspondingly designated by the same reference character with a single prime exponent, and it is to be noted the only differentiating feature consists in substituting for the return bend freely rotative ball bearing grooved-rollers 22. In order to journal the rollers 22, the recess 12' is extended at 23 in the region of each roller 16', and a hole 24 is bored radially through the head body 9' into the boss 11' for insertion of a suitable axis pin 25 on which the associated roller 22 freely rotates; or contrariwise said roller may be secured to the axis pin 25 and the latter revolve in the boring 24. In practice, the groove of each roller 22 is, preferably, slightly inset at one side to provide the return bend 18' and outwardly flared at 18'', and respectively function to facilitate rounding of the container body shell contacting edge incidental to commencement of the spinning operation and for initial smooth guidance of said edge into the roller groove 22, all of which will be obvious to those conversant with the art.

In Fig. VI there is shown an additional ball bearing roller 26, journaled by an axis pin 27 fitting a boring 28 in the body 9', said roller 26 being freely rotative in a conformatory pocket 29 provided for its reception in the wall of the head 8'. It is to be remarked the cylindrical portion of the roller 26 projects very slightly inwards of the recess 12', while its lower portion is conically truncated at 30 to coincide with the head flaring 18'. These rollers 26 coact with the rollers 16' to facilitate free entry of the container body shell 7' into the recess 12', as well as to materially reduce frictional binding between said body shell and the head during the spinning operation.

Obviously the number of rollers 16, 22 and 70

26 employed may be varied in number and to meet different service conditions of the spinning heads 8. In practice it has been found that a pair of diametrically opposed ball-bearing rollers 16 alone are extremely efficient for the spinning of paper, fiber and analogous material container body shell ends. It will also be readily understood that the grooved rollers 22 and auxiliary rollers 26, while expediting the spinning-sealing operation, are highly advantageous when treating heavier material containers, as well as those fabricated from sheet metal.

From the foregoing disclosure it will be appreciated the invention fully justifies the stated objects had in view, and while specific embodiments have been particularly described, the following claims are to be accorded such reasonable range of equivalents as their interpretative scope, and the prior art, will permit.

Having thus described my invention, I claim:

1. A rotary head for spinning the free edges of container body shells having pre-inserted closures, comprising a body portion with an attaching section, said body portion including an interior coaxial boss defining an annular recess having a flaring entrant part and a return bend remote therefrom, circumferentially spaced substantially-circular cut-outs in said boss, and outwardly-active freely revolvable ball-bearing rollers in said cut-outs of a depth less than that of the cut-outs and with slight circumferential projection into the recess for firmly compressing the container retroverted end into mutual union with the confronting body shell wall as well as the peripheral outer surface of the adjoining closure.

2. A rotary spinning head as defined in claim 1, wherein headed screw studs secure the inner races of the ball-bearing rollers in place while the outer races have slight projection beyond the circumferential wall of the head boss.

3. A rotary spinning head as defined in claim 1, further characterized by grooved ball-bearing rollers operative as return bend means, said grooved rollers being located in the body portion annular recess and serving to facilitate retroversion of the container body shell, and each such grooved roller being associated with one of the outwardly-active compressing rollers.

4. A rotary spinning head as defined in claim 1, further characterized by circumferentially-spaced ball-bearing rollers journaled in conformative pockets in the recess outer wall, each said roller embodying a frusto-conical part for planar coaction with the recess entrant flare and the other part cylindrical for opposing coaction with one of the rollers in the body portion coaxial boss for the joint compression of the body shell retroversion.

5. A rotary spinning head as defined in claim 1, further characterized by circumferentially-spaced grooved ball-bearing rollers housed in cut-outs through the annular recess inner end, each said roller having the groove inset at one side with the opposing side slightly flared circumferentially, and said roller groove insets jointly serving as return bends for initial slight outward projection of the container body shell free edge.

JOHN K. M. HARRISON.
